UNITED STATES PATENT OFFICE.

RALPH H. TUCKER, OF LOS ANGELES, CALIFORNIA, ASSIGNOR OF ONE-THIRD TO EDGAR S. CAMERON AND ONE-THIRD TO CHARLES M. TUCKER, BOTH OF LOS ANGELES, CALIFORNIA.

AIR-LIFT PUMP.

1,334,638.

Specification of Letters Patent. Patented Mar. 23, 1920.

Application filed February 24, 1919. Serial No. 278,804.

To all whom it may concern:

Be it known that I, RALPH H. TUCKER, a citizen of the United States, residing at Los Angeles, in the county of Los Angeles 5 and State of California, have invented new and useful Improvements in Air-Lift Pumps, of which the following is a specification.

My invention relates to air lift pumps 10 and consists of the novel features herein shown, described and claimed.

Figure 1 is a fragmentary section of an oil well lined with a casing and provided with an air lift pump embodying the principles of my invention, the pump being 15 shown in elevation.

Fig. 2 is an enlarged fragmentary vertical central sectional elevation on a plane parallel with Fig. 1 and showing the construction of the pump.

Fig. 3 is a horizontal cross section on the line 3—3 of Fig. 2.

Fig. 4 is a horizontal cross section on the line 4—4 of Fig. 2.

An oil well hole 1 may be of any practical depth and an oil well casing 2 may extend to the bottom of the hole 1. A flange 3 may be fixed to cover the upper end of the hole 1 and to cover the upper end of the casing 2. An air lift pump 4 is mounted through the flange 3 and extends downwardly into the casing 2 to a point below the level of the oil in the casing or to the bottom of the casing.

At the lower end of the pump there is a settling basin 5 consisting of an internal coupling 6, an external coupling 7 screwed upon the lower end of the coupling 6, a pipe section 8 screwed into the coupling 7 and of considerable length and size, a coupling 9 screwed upon the lower end of the pipe section 8 and a plug 10 screwed into the coupling 9. The settling basin 5 is preferably thus made up of pipe fittings 45 so that it can be readily assembled and made of any desired size and length and so that it may be readily taken apart.

A pump head 11 is connected directly to the top of the settling basin 5 and consists 50 of a cross 12 having one end screwed upon the internal coupling 6 and having a pump pipe 13 screwed into an opening in line with the coupling 6. Air lift mechanism 14 is mounted within the pump head 11 and the pump pipe 13. A pipe nipple 15 is screwed

down into the reduced upper end of the internal coupling 6. An external coupling 16 is screwed upon the upper end of the pipe nipple 15. A long pipe nipple 17 is screwed down into the coupling 16 and has 60 radial slots 18 in its upper end. A plug 19 is screwed into the upper end of the pipe 17 and a deflector 20 is screwed up into the plug 19 and has a point 21 on a level with the top of the coupling 16, said 65 deflector 20 being circular in cross section and mounted at the axial center of the pipe 17. A pipe 22 is inserted through a small opening drilled in one side of the pump head 11 and tapped through the coupling 70 16 between the ends of the pipes 15 and 17, and an air pipe 23 is connected to the pipe 22 by a coupling 24 and extends upwardly through the flange 3 and to the source of air supply. Clips 25 connect the pipe 23 75 to the pump pipe 13 so as to steady the air pipe which is considerably smaller than the pump pipe.

In the practical operation air is forced down the pipe 23 through the pipe 22 to a 80 chamber 25, then through the coupling 16 and pipe 17. The oil flows into the pump head 12 through side openings 26 and 27 to a chamber 28 within the pump head 11 and the pump pipe 13 and rises above the radial 85 slots 18. The air passing upwardly through the chamber 25 through the radial slots 18 will be under the oil above the slots 18 and will force the oil to flow upwardly in the pump pipe 13. A T 29 is fixed upon the upper end of the pump pipe 13 above the flange 3, the upper end of the T being closed by a plug 30, and a side outlet 31 of the T is left open so that when the oil flows upwardly through the pipe 13 it will be discharged 90 outwardly through the side outlet 31. The point 21 of the deflector 20 serves to divide the stream of oil flowing upwardly in the chamber 25 so that the streams passing 95 through the slots 18 will be practically equal.

The closure at the upper end of the pipe 17 may be a cap instead of a plug and the pipe 22 may be made up of nipples and an elbow instead of being bent.

The trouble with air lift pumps has been 105 the great difficulty in removing the pump and the great liability of the pump clogging with sand so as to require frequent removals. My air lift pump may be readily removed from the well and cleaned, changed, repaired 110

and returned to the well, and the use of the settling basin 5 makes it unnecessary to remove the pump frequently because the sand which usually settles in the bottom of the air lift pump head and clogs the pump will pass downwardly into the settling basin 5, and under ordinary conditions the pump will run a considerable length of time before the settling basin is filled sufficiently to clog the 10 pump head.

Various changes may be made without departing from the spirit of my invention as claimed.

I claim:

- 15 1. An air lift pump, comprising a pump head having an inlet; means forming a settling basin extending downwardly from the pump head; an air distributing means extending upwardly from the settling basin 20 within the pump head; and an air pipe connected to the pump head to discharge into the air distributing means.
2. An air lift pump comprising a head forming a main chamber, an air stand pipe 25 extending upwardly in and from the bottom of the main chamber having a closed top and air discharge ports comprising narrow slots disposed longitudinally of the stand pipe adjacent to the top thereof, a settling

basin extending below the main chamber and 30 communicating with the air stand pipe, and an air conduit connecting with the air stand pipe below the slots.

3. An air lift pump comprising a head forming a main chamber having an inlet 35 means, an air stand pipe extending upwardly within the main chamber having a closed top, air discharge ports comprising narrow slots disposed longitudinally of the stand pipe adjacent to the top thereof, a 40 settling basin extending below the main chamber and communicating with the air stand pipe, and a means for conducting air to the stand pipe below the slots from outside of the main chamber.

4. An air lift pump head comprising a main chamber having an inlet means, an air stand pipe extending upwardly within the main chamber having a closed top and air discharge ports adjacent to the top, means 50 for conducting the air to the stand pipe below the discharge ports, and means within the stand pipe disposed between the discharge ports and the air inlet means for distributing the air equally to the ports. 55

In testimony whereof I have signed my name to this specification.

RALPH H. TUCKER.
